GARBAGE CAN HOLDER

Lonnie F. Goodman, 817 SW. 23rd St.,
Oklahoma City, Okla. 73109

Filed Feb. 5, 1970, Ser. No. 21,278

Term of patent 14 years

Int. Cl. D12—02

U.S. Cl. D14—3

FIG. 1 is a perspective view of a garbage can holder constructed in accordance with the present invention.

FIG. 2 is an elevational view of one end of the garbage can holder shown in FIG. 1.

FIG. 3 is an elevational view of the opposite end of the garbage can holder shown in FIG. 1.

FIG. 4 is a bottom plan view of the garbage can holder of FIG. 1.

I claim:

The ornamental design for a garbage can holder, substantially as shown.
